UNITED STATES PATENT OFFICE.

CHARLES H. FOSTER, OF NEW YORK, N. Y., ASSIGNOR TO UNION SPECIAL SEWING MACHINE COMPANY, OF CHICAGO, ILLINOIS, A CORPORATION OF ILLINOIS.

MACHINE FOR SEWING FILLED BAGS.

No. 875,513.

Specification of Letters Patent.

Patented Dec. 31, 1907.

Application filed June 14, 1902. Serial No. 111,712.

To all whom it may concern:

Be it known that I, CHARLES H. FOSTER, of New York, in the county of New York and State of New York, have invented certain new and useful Improvements in Machines for Sewing Filled Bags; and I do hereby declare that the following is a full, clear, and exact description thereof, reference being had to the accompanying drawings, and to the letters of reference marked thereon, which form a part of this specification.

My invention relates to an improvement in machines and apparatus for sewing filled sacks of the type especially illustrated in my application for patent filed May 10, 1901, Serial No. 59,822.

In the practical embodiment of the invention set forth in the above entitled application, it has been found desirable to provide a mechanism which can be readily adapted for use with sewing machines whether the stitches of the sewing machine are set, say eight to the inch, as is usual in sewing cloth sacks, or four, as is usual in sewing paper sacks, or for any other number as may be desired. Furthermore, it has been found desirable to provide a simple arrangement for holding the cones of the power transmitter in engagement to drive the machine without necessitating the shifting of the feet of the operator from floor to treadle and the like. Again, it has been found desirable to provide a cutting arrangement for cutting off the chain of stitches between the bags which shall be thrown into and out of operation by the operator, but the actual cutting and returning action of which shall be automatic.

The invention, therefore, includes, in an apparatus for sewing filled sacks, an improvement in mechanism for taking up the slack in the conveying belt, a novel mechanism for driving the conveying belt, and a mechanism for throwing the driving mechanism for the conveying belt and sewing machine into and out of operation. All these details form part of the apparatus for sewing filled bags and are herein claimed.

The invention is illustrated in the accompanying drawings, in which

Figure 1 is a front elevation of so much of an apparatus of the type referred to as is necessary to a complete understanding of my invention; and Fig. 2 is a side elevation of the same.

In the drawings, the sewing mechanism is

herein embodied in a sewing machine of the Union Special type such as illustrated in Patents 547,675 and 547,676, of October 8th, 1895, and is represented by the letter A. It is attached to a table or support B, preferably of the construction illustrated in my application aforesaid. The driving shaft of the sewing machine is arranged vertically and the gooseneck C overhangs the edge of the table or support, the needle working in a horizontal plane. These parts being of well known construction need not be more specifically referred to.

On the under side of the table is supported a counter-shaft F having the usual power transmitter and clutch mechanism, a belt *a* passing over one of the cone pulleys serving to transmit motion to the belt wheel on the driving shaft of the sewing machine.

The bracket *i* which carries the pulleys over which the conveying belt *h* is stretched and operates, differs from that shown in the aforesaid application, in that it is provided with right and left extension brackets G, H. The right-hand extension G is guided in ways upon the bracket *i*, and supports the shaft *k* of the right-hand conveying belt pulley *g*. The extension bracket can be adjusted by loosening the bolt *I* and adjusting the screw *K*, which bears on the inner end of the extension bracket G, thus the slack in the conveyer belt may be taken up as desired, or shorter or longer belts may be used.

A belt *b* runs from a small cone on the driver over an idle pulley *j* to a pulley *H'* on the upright shaft *Q* and transmits motion to the worm wheel *f* in the manner set forth in my aforesaid application. The shaft *k'* upon which the worm wheel is supported is also provided with a sprocket wheel *L* over which is trained a sprocket chain *M* which drives the belt pulley *g'* supported in the left-hand extension bracket *H*. By this arrangement a change in the speed of the conveyer belt, commensurate with the number of stitches to the inch made by the sewing machine, may be effected, the sprocket wheel *L* being removed and another substituted therefor.

T is a board for supporting the conveyer belt and U an arm supporting the board. Said board T is carried by suitable brackets which slidingly engage the end pieces of the framework and said brackets together with the supporting board and conveyer belt are

supported and moved vertically by sprocket chains located at each end of the frame, one end of said sprocket chain being connected to each bracket and the other end to a suitable counter-weight. This sprocket chain passes over sprocket wheels near the upper end of the frame which are mounted on a common shaft adapted to be operated by a hand crank. This matter is all clearly 10 shown in my co-pending application 59,822 and will not need further description in this connection.

It has been found in connection with the sewing of large and heavy sacks that it is 15 very tiresome for the operator to stand upon one leg while the other is upon the treadle to hold the cones of the power transmitter in engagement to drive the machine. This one foot has constantly to be changed from 20 the treadle of the power transmitter to the treadle of the cutter.

As a further and special improvement in machines of this character and to avoid this inconvenience, I have provided a knee lever 25 N, which is adapted to oscillate the shaft O, journaled in a bracket P and having an arm V connected at its outer end through the rod or chain R with the operating arm of the clutch lever S. This lever N may, of course, 30 be manipulated by hand, if desired, but it is convenient to have it so arranged that when the attendant is standing in position to manipulate the apparatus, by pressure of his knee against the lever the clutch may be 35 held so that the parts are driven.

As a still further and special improvement in an apparatus of this character, I have provided a novel arrangement for severing the chain of stitching after a sack has been 40 sewed, in a semi-automatic manner. Referring to the drawings, 1 is one of the band pulleys of the constantly revolving member of the power transmitter which is fitted with a belt which is trained over a pulley 2, supported upon a shaft 3, journaled in bearings 45 upon the bracket which supports the sewing machine. Upon this shaft 3 is fastened a disk 4, provided with a projecting pin 5, the shaft and disk being, of course, constantly 50 run along with the constantly running part of the power transmitter.

So far as the cutter itself is concerned, the arrangement is substantially the same as shown in my application for patent filed 55 April 5, 1899, Serial No. 711,801, in which a pivoted lever 6 is adapted to engage at the head of the knife supporting shaft and force it down against an anvil 7 supported upon the lower end of the cylindrical bed plate of 60 the sewing machine. From the upper end of the pivoted lever which is pivoted on the gooseneck projects horizontally a lever 8, which at its inner end passes through the upper end of a vertical lever 10, pivoted at 65 11 to the machine frame. A head on the inner

end of the lever 9 prevents said lever from being withdrawn through the vertical lever, and the seat for said lever 9 in the upper end of the vertical lever 10 is formed to allow movement of said vertical lever on its pivot. 70 The upper end of the vertical lever is normally pressed outwardly by means of the spring 12. The vertical lever 10 at its lower end is pivoted to a horizontal lever 13 which has a downwardly projecting part 14 to 75 which is attached a spring 15 normally retaining the same in the position shown in the right-hand dotted lines in Fig. 2. This horizontal lever is provided at its outer end with a notch or projection normally engaging the 80 pin 5 on the disk 4 and beyond the projection slants upwardly and is adapted to be brought into engagement with a roller 16 on the bracket 17, whereby in the upward movement of the horizontal lever it is swung on its 85 pivot and tripped out of engagement with the pin 5. At its forward end the horizontal lever is adapted to be engaged by a pin 20 which is tripped by a bell-crank lever, 21 journaled on the bracket 17. When the 90 bell-crank lever is moved to draw back the pin 20 the horizontal lever through the action of the lower spring is forced downwardly, so that its notch engages the pin 5 and said horizontal lever is then swung rearwardly carrying also the lower end of the vertical lever 10, thus forcing the upper end of the vertical lever forward against the pressure of its spring, and causing the knife to 95 operate to cut the chain of stitching. When the beveled end of the horizontal lever rides up over the pin 20, it is forced out of engagement with said pin 5 and the parts are returned to normal position by the action of the two springs. This cutting apparatus 100 forms the subject matter of another application filed by me on the 26th day of January 1903, Serial No. 140,647.

Various minor modifications and changes may be made without departing from the 110 spirit of my invention.

Having thus fully described my invention, what I claim as new and desire to secure by Letters Patent is:

1. In a filled bag sewing apparatus, the 115 combination with a supporting frame, a sewing machine supported thereby and having its head overhanging said frame, stitch forming mechanism carried by said head, a vertically adjustable support beneath said 120 stitch forming mechanism, a conveying belt carried by said support, means for tightening said belt, and means for driving said belt including a removable sprocket wheel whereby by the removal of said sprocket and the substitution of another the speed of the conveying belt may be changed, substantially as described.

2. In a filled bag sewing apparatus, the 130 combination with a suitable frame, of the

sewing mechanism the elements of which overhang the top of said frame, a vertically adjustable support beneath said sewing mechanism and of greater length than said frame, brackets upon said support, pulleys upon said brackets and a conveyer belt trained over said pulleys, one of said brackets being longitudinally adjustable; substantially as described.

10 3. In a filled bag sewing apparatus, the combination with a suitable frame, of the sewing mechanism the elements of which overhang the top of said frame, a vertically adjustable support beneath said sewing mechanism and of greater length than said frame, brackets upon said supports, pulleys upon said brackets, and a conveyer belt trained over said pulleys, one of said brackets being guided in ways on the support, an end 15 screw for adjusting the bracket longitudinally, and means for securing it in adjusted position; substantially as described.

4. In a filled bag sewing apparatus, the combination with a suitable frame, of the 20 sewing mechanism, the elements of which overhang the top of said frame, a vertically adjustable support beneath said sewing mechanism, pulleys carried by said support, a conveyer belt trained over said pulleys, and 25 means for driving the conveyer belt, comprising two parallel shafts having sprocket wheels thereon; one having a gear connection with the driving mechanism of the machine, and the other on the shaft carrying one of the 30 conveyer belt pulleys, and a sprocket chain connecting the two wheels; substantially as 35 described.

5. In a filled bag sewing apparatus the combination with a suitable frame of a sewing mechanism the elements of which overhang the top of said frame, a bag table beneath said sewing mechanism, an endless conveyer belt upon said table, common driving means for said sewing mechanism and the conveyer belt, a power transmitter, a clutch 40 for causing the same to engage and disengage the parts to be driven, and a starting shifter projecting from said table for movement laterally by the leg of the operator, and connections between the shifting lever and the clutch; substantially as described.

6. In a filled bag sewing apparatus the combination with a suitable frame of a sewing mechanism overhanging the top of said frame, a bag table beneath said sewing mechanism, an endless conveyer belt upon said table, common driving means for said sewing mechanism and the conveyer belt, a power transmitter, a clutch for causing the same to engage and disengage the parts to be driven, 55 and a starting shifter projecting from said table for movement laterally by the leg of the operator, and connections between the shifting lever and the clutch, said connections including the shaft O, the arm V and the connection R; substantially as described.

In testimony that I claim the foregoing as my invention I affix my signature in presence of two witnesses, this 24th day of May, A. D. 1902.

CHARLES H. FOSTER.
